UNITED STATES PATENT OFFICE.

WILLIAM SIMMS, OF ELGIN, ILLINOIS.

MULTIPLE TABLE.

1,227,681.

Specification of Letters Patent. Patented May 29, 1917.

Application filed February 23, 1916. Serial No. 80,044.

To all whom it may concern:

Be it known that I, WILLIAM SIMMS, a citizen of the United States of America, residing at Elgin, in the county of Kane 5 and State of Illinois, have invented certain new and useful Improvements in Multiple Tables, of which the following is a specification, reference being had therein to the accompanying drawing.

10 This invention relates to a table and has for its object the production of a table that can be placed in a certain way to be used as a single table.

Another object of this invention is to 15 provide a device that can be used as two, three or more separate tables.

With these and other objects in view this 20 invention consists of certain novel features of construction, combinations and arrangements of parts as will be more fully described and pointed out in the appended claims.

In the accompanying drawing:

Figure 1 is a view of the improved table 25 with its sections taken apart.

Fig. 2 is a section taken through the improved table when in a compact position.

Fig. 3 is an enlarged section of the leg 30 of the upper section fitting within the hollow leg of the intermediate section.

This table consists of three parts, the base section 10, an intermediate section 11, and the upper section 12. The base section 35 10 is provided with a plurality of hollow legs 13 which are adapted to receive the hollow legs 14 of the intermediate section 11 which in turn are adapted to receive the solid legs 15 of the upper section 12. These sections 10, 11, and 12 are provided 40 with tops 16, 17, and 18 respectively.

Hinges 19 are secured to the upper ends 45 of the hollow legs 13 and 14 of the section 10 and 11 and are positioned flush with the tops 16 and 17 of these sections. These 50 hinges 19 are also secured to gates 20 which are adapted to swing over and close the opening of the hollow legs 13 and 14 at the tops 16 and 17. The hollow legs 13 and 14 are provided with a notch 21 which is 55 of substantially the same depth as the thickness of the gates 20 and is adapted to receive these gates 20 when they are in a closed position thus making a flat surface over the opening of these hollow legs with the tops 16 and 17.

Formed on the under face of the tops 17

and 18 of the sections 11 and 12 are pockets 22 adapted to receive the gates 20 when they are in an open position. These pockets 22 enable these sections to be placed flush 60 upon each other as clearly shown in Fig. 3, as the pockets 22 are of substantially the same depth as the thickness of the gates 20.

From the foregoing description it will be seen that when it is desired to use this table 65 as one, it can be easily done by inserting the sections within one another as shown in Fig. 2. This makes a very compact and durable table and is free from any lateral movement of the sections relative to one 70 another. When it is wished to use these tables separately it can be done by removing the sections from one another and merely swinging the gates over the openings caused in the tops of the respective 75 sections by the hollow legs, and a smooth neat looking surface will be made. These tables can also be used for display purposes, that is, setting one upon the other as the gates could be swung over the openings and 80 the legs of the respective sections resting upon the top of the section beneath it.

Various changes in the form, proportion, and minor details of construction may be resorted to without departing from the 85 principle, or sacrificing any of the advantages of the invention as defined in the appended claims.

Having thus described the invention what 90 is claimed as new, is:—

1. A table comprising a plurality of sections, each section comprising a top portion and a plurality of legs, all of said sections with the exception of the uppermost one provided with hollow legs adapted to open 95 through the top portions thereof so as to receive the legs of an adjacent section, gates secured to the upper end of said hollow legs and adapted to swing over the same for constituting a smooth surface on the 100 top of each section, and pockets formed adjacent said legs for receiving the gates of their respective lower sections when the gates are in an open position.

2. A table comprising a plurality of sections, each section comprising a top portion and a plurality of legs, all of said legs with the exception of those on the top section being hollow and adapted to open through the top portion of their respective sections 110 so as to receive the legs of an adjacent section, gates secured to the upper ends of said

hollow legs, cut-away portions formed adjacent said hollow legs at the hinged side of said gates, recesses formed adjacent the opposite side of said hollow legs, said cut-away portions and said recesses being substantially the same depth as the depth of said gate and adapted to receive said gate

when in a closed position whereby the same will be flush with the top portion when closed.

10

In testimony whereof I hereunto affix my signature.

WILLIAM SIMMS.
